CLAIM

The ornamental design for an artificial lash extension separating comb as shown and described.

DESCRIPTION

FIG. 1 is a top left perspective view of an artificial lash extension separating apparatus in accordance with the claimed design.

FIG. 2 is a left side view thereof.

FIG. 3 is a right side view thereof.

FIG. 4 is a top view thereof.

FIG. 5 is a bottom view thereof.

FIG. 6 is a front view thereof; and,

FIG. 7 is a rear view thereof.

The broken lines consisting of evenly spaced lines in the figures show portions of the artificial lash extension separating apparatus that form no part of the claimed design. The dash dot lines illustrate boundaries of the claimed design and form no part of the claimed design.
